(57) **CLAIM**

The ornamental design for a ceiling fan blade, as shown and described.

DESCRIPTION

FIG. 1 is a side perspective view of a ceiling fan blade, showing the new design;

FIG. 2 is a front view;

FIG. 3 is a back view;

FIG. 4 is a side view with the opposite side being a mirror image; and,

FIG. 5 is a top view with the bottom view being a mirror image.

The broken line showing of portions of the ceiling fan blade is included for the purpose of illustrating environmental structure and forms no part of the claimed design.

1 Claim, 2 Drawing Sheets
